VACUUM CLEANER

Stanley F. Lachowicz, New Britain, Conn., assignor to Landers, Frary & Clark, New Britain, Conn., a corporation of Connecticut

Application January 6, 1956, Serial No. 557,766

11 Claims. (Cl. 183—37)

This invention relates generally to vacuum cleaners and more particularly to an improved construction for vacuum cleaners of the tank type.

It is a general purpose of the invention to provide a tank type vacuum cleaner which is rugged yet light weight and simple and economical to manufacture, and which will incorporate improved and more efficient air flow characteristics.

It is a more specific object of the invention to provide, in a tank type vacuum cleaner of the type having a vertically arranged dust bag compartment and a horizontally arranged fan and motor assembly, a novel and improved air flow arrangement between the dust bag compartment and the fan and motor assembly.

It is another object of the invention to provide a novel and improved arrangement for mounting the fan and motor assembly which will improve the operation of a machine of the type described with respect to vibration and noise level, and which will further result in a more compact and economical structure.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a longitudinal vertical cross sectional view of a tank type vacuum cleaner constructed in accordance with the invention;

Fig. 2 is an elevational view of the dust bag compartment of the machine of Fig. 1 illustrating one of the elements of the invention; and

Fig. 3 is a fragmentary cross sectional view of a portion of the vacuum cleaner of Fig. 1.

With reference to the drawings, a cleaner constructed in accordance with the invention is comprised of a generally rectangular box-like sheet metal outer housing 10, which for convenience in manufacture may comprise an upper shell or section 11 and a lower shell or section 12. The upper and lower sections are provided with cooperating peripheral flanges 13 and 14 respectively, which are connected together such as by screws 15. A strip 16 of resilient material such as rubber or plastic surrounds the flanges 13 and 14 to provide a bumper for the cleaner and to cover the joint between the interconnected sections of the housing.

Disposed vertically within the outer housing and spaced laterally from the side walls of the outer housing is a dust bag compartment 20. The compartment 20, as can be seen from Fig. 1, extends substantially the full height of the outer housing with its open end extending upwardly. The bottom 21, of the compartment, as can be seen in Fig. 1, is curved inwardly and upwardly from the periphery thereof to form a concave annular portion directed inwardly of the compartment and having an apex

2

disposed coaxially of the compartment. The compartment is mounted on the base 22 of the lower shell section 12 by means such as the screws 23 extending upwardly through the base into engagement with the bottom 21 of the compartment adjacent the periphery thereof. A cover 24 is hingedly mounted at 25 to the top of the upper shell 11 to provide a means for closing the open end of the compartment 20. A latch 26 is provided to retain the cover in closed position. The cover 24 incorporates as at 27 means for attaching a hose thereto in communication with the interior of the dust bag compartment 20.

The top of the upper shell 11 is provided with a downwardly directed flange 30 having an inwardly directed rim portion 31 on which is mounted a ring 32 fabricated from suitable resilient material such as rubber or plastic. The inner diameter of the ring 32 engages the outer diameter of the top of the dust bag compartment 20 to position the open end of the compartment in registry with the cover 24. A ring 33 is supported on the ring 32 and in turn supports a ring 34, to which is mounted a cloth bag 35 which extends inwardly of the dust bag compartment 20. A paper dust bag 36 is supported at its open end from a ring 37 which is supported by the cloth bag ring 34.

The lower portion of the dust bag compartment 20 is reduced in diameter to form an inclined surface 38, on which is supported a filter pad retainer 39. The filter pad retainer 39 is held in position by means such as the screw 40 extending through the retainer, and engaged with the apex of the upwardly directed portion of the bottom of the compartment 20. The retainer 39 has a radially inwardly directed shoulder 45 on which is supported a filter pad 46. The lower surface of the retainer 39 is provided with a plurality of perforations as at 47 to permit the passage of air through the filter pad retainer.

The side wall of the compartment 20 is provided with an elongated horizontally directed aperture 48 adjacent the bottom thereof and in communication with the underside of the filter pad retainer 39. A vertically disposed air duct element 49 fabricated preferably from sheet metal is mounted along the side of compartment 20 by means such as the rivets 50. A ring preferably of rubber or the like is mounted intermediate the air duct element 49 and the side of the compartment 20 to form an airtight connection between the duct and the compartment, and as will be later seen, to reduce vibrations within the machine. The air duct element 49 is provided with a horizontally directed aperture 51 adjacent the upper end thereof which is surrounded by a horizontally extending flange 52. As can be seen from the drawings, the air duct element 49 in cooperation with the side of the compartment 20, forms a wide enclosed air passageway 63 between the aperture 48 in the compartment 20 and the aperture 51 of the air duct element. The passageway 63 is unobstructed and provides minimum resistance to air flow between the compartment and the aperture 51.

A fan and motor assembly 53 is disposed horizontally within the outer housing 10 and externally of the dust bag compartment 20 in spaced relation to the sides of the outer housing. The motor end 61 of the assembly 53 is mounted on a motor mounting bracket 54 connected to the bottom of the lower shell 12 by means such as screws 55. The bracket 54 extends upwardly and is provided at its upper end with a cup-like portion 56 in which is received a resilient disc 57 fabricated from suitable material such as sponge rubber. The cup-like portion 56 and disc 57 are provided with coaxial apertures in which are received an axial extension 60 of the fan and motor assembly and as can be seen from Fig. 1, the axial extension 60 is provided with a threaded axial

bore 65. A disc 66 also fabricated preferably from material having resilient qualities such as sponge rubber and the like is mounted on the axial extension 60 on the other side of the cup-like portion 56, relative to the disc 57. A plate 67 and a plate 68 are engaged with the disc 66 and the disc 57 respectively, with a shoulder 62 on the axial extension limiting the axial movement of the plate 67 relative to the axial extension 60. These plates in cooperation with a bolt 69 threadably received within the axial bore 65 serve to compress the discs 66 and 57 therebetween, to provide a resilient support for the motor end 21 of the fan and motor assembly. A washer-like member 70 disposed between the plate 68 and the end of the axial extension 60 limits the compression of the discs to that necessary for proper support of the fan and motor assembly. As can be seen from Fig. 1, the aperture in the mounting bracket 54 is larger than the axial extension 60, thus permitting the fan and motor assembly to move relative to the mounting bracket as provided by the resiliency of the discs 57 and 66. Thus, it can be seen that there has been provided a means for mounting the motor end 61 of the motor so as to substantially eliminate the transfer to the remainder of the cleaner of any vibration due to operation of the fan and motor, and thus reduce the noise level of the machine.

It has been found in a vacuum cleaner constructed, as thus far described, with a horizontally disposed fan and motor assembly that there is a tendency for the fan and motor assembly to be rotated about its rotation axis when the motor is first energized due to the starting torque of the motor. This rotation of the fan and motor assembly of course cannot be permitted for obvious reasons. Therefore, in accordance with the invention, the plate 67 is, as can be seen in Fig. 3, provided with an extension or finger 85 directed radially of the plate and having an end portion 86 directed axially of the fan and motor assembly and bifurcated to provide a pair of spaced apart members, as at 87, which engage either side of a radially disposed protuberance or rib 88 on one end of the fan and motor assembly. The plate 67 is further provided with an axially extending projection preferably in the form of the struck-out tab 89 which is received in a radially extending aperture or slot 90 in the resilient disc 66. The disc 66 is also provided with a second radially extending aperture or slot 91 diametrically disposed relative to the slot 90 and in which is received an axially extending projection 92 on the cup-like portion 56 of the motor mounting bracket 54. The projection 92 is also preferably in the form of a struck-out tab. It can thus be seen that there has been provided a novel means of restraining rotation of the fan and motor assembly relative to the outer housing 10, which restraining means is simple and economical to manufacture and which provides a resiliency which is desirable to maintain the vibrations and attendant noise level of the machine at a minimum.

The other end of the fan and motor assembly is, in accordance with the invention, supported by the air duct element 49. As can be seen from the drawings, the fan and motor assembly is provided with a casing member 71 serving to limit the inlet of air to the fan 72 to the aperture formed by the axially directed flange 73 of the casing member 71. A sleeve 74 is mounted within the flange 73 and has a flange 75 in engagement with the inner surface of the casing member 71. The combined diameters of the flange 73 and sleeve 74, as can be seen from Fig. 1, are less than the inner diameter of the air duct flange 52 and the sleeve 74 projects inwardly of the aperture 51 formed by the flange 52 to form an air passageway between the fan and the air passageway 63. In accordance with the invention, there is disposed between the inner diameter of the flange 52 and the outer diameter of both the sleeve 74 and flange 73, a large bushing or collar 78 of suitable resilient ma-

terial such as rubber, which provides a resilient support for the casing member 71, and thus the fan end of the fan and motor assembly on the air duct element 49. This means of mounting the fan and motor assembly to the air duct 49 provides, of course, an increase in the economy of manufacture of the cleaner as well as providing a vibration-absorbing mounting to substantially reduce the overall noise level of the machine. As noted above, the manner of supporting the motor and fan assembly on the air duct 49 also serves to provide an enclosed, low pressure drop air passageway for the flow of air from the air passageway 63 to the inlet side of the fan.

In the operation of the machine as a suction cleaner, air is drawn through the dust bag compartment 20 and its aperture 48, through the air passageway 63, and into the fan 72 through the duct formed by the sleeve 74. Air is directed from the outlet side of the fan through a passageway 76 in the motor and fan assembly into the motor and thence outwardly through the stator 77 of the motor for expansion into the spaced interior of the outer housing 10 externally of the motor and fan assembly 53, the dust bag compartment 20, and their interconnecting air passageways. This expansion of the air into the interior of the housing, rather than immediately directing the air from the fan through a restricted opening to the atmosphere outwardly of the housing serves to further reduce the overall noise level of the machine. The exhaust air in the interior of the housing is permitted to flow outwardly thereof through an aperture 79 provided in one end of the outer housing 10. An escutcheon plate 80 is mounted such as by a bead 81 to the outer housing and has mounted thereon a hose connection 82 in registry with the aperture 79. A filter element 83 such as a flock screen is mounted within the outer housing in registry with the aperture 79 and is retained in place by the engagement of a peripheral lip thereof between the escutcheon plate 80 and the outer housing 10 as at 84.

The advantages of the novel structure herein described should be apparent from the above description. The mounting of the fan and motor assembly in the horizontal position rather than a vertical position, of course, reduces the loads on the thrust bearings of the motor and fan assembly, inasmuch as the weight of the assembly is not added to any thrust loads imposed on the bearings; the passage of air from the dust bag compartment to the fan is free and unobstructed, and is accomplished by the most direct route possible, eliminating any tortuous redirections of the air in its flow; and most particularly the supporting of one end of the fan and motor assembly on the air duct element 49 provides the novel combination of a simplified means of mounting of the fan and motor assembly with an improved air passageway arrangement between the fan and the dust bag compartment.

It can thus be seen that there have been provided novel improvements in the construction of a tank type vacuum cleaner resulting in increased economy and simplicity of manufacture, and providing improvement in the air flow characteristics of the machine, as well as a reduction in the vibration and attendant noise level of the overall machine.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention

which, as a matter of language, might be said to fall therebetween.

I claim:

1. In a vacuum cleaner of the tank type, an outer housing, a vertically arranged dust bag compartment within the outer housing, means forming an aperture in the side of said compartment adjacent the bottom thereof, means forming a vertically disposed air duct externally of the compartment, said air duct communicating at one end with said aperture in said compartment and being provided with a horizontally directed aperture adjacent its other end, a horizontally disposed fan and motor assembly within and spaced from the outer housing having an inlet air passageway at one end, means connecting said one end of fan and motor assembly to said means forming said air duct for the support of said one end of the fan and motor assembly thereby and forming an enclosed air passageway connecting said inlet air passageway with said horizontally directed aperture in the air duct, and means on the outer housing resiliently supporting the other end of said fan and motor assembly.

2. In a vacuum cleaner of the tank type, an outer housing, a vertically arranged dust bag compartment within the outer housing, means forming an aperture in the side of the compartment adjacent the bottom thereof, a vertically disposed duct element mounted on the periphery of the compartment to form in cooperation with the outer peripheral surface of the compartment an enclosed air passageway communicating at one end with said aperture in the compartment, the duct element being provided with a horizontally directed aperture adjacent the other end thereof, a horizontally disposed fan and motor assembly within and spaced from the outer housing having an inlet air passageway at one end, means connecting said one end of the fan and motor assembly to the air duct for support thereby and forming an enclosed air passageway connecting said inlet air passageway with the horizontally directed aperture in the air duct, and a resilient support for the other end of the fan and motor assembly mounted on the outer housing.

3. In a vacuum cleaner of the tank type, the combination comprising an outer housing, a vertically arranged cylindrical dust bag compartment within the outer housing, the bottom of the compartment being curved radially inwardly and upwardly from the periphery thereof, filter means disposed internally of the compartment and supported on the apex of the bottom of the compartment, the compartment being provided with an aperture in a vertical side thereof communicating with the under side of the filter means, a vertically disposed duct element mounted on the outer periphery of the compartment to form in cooperation with the compartment an enclosed air passageway communicating at one end with the aperture in the side of the compartment, the duct element being provided with a horizontally directed aperture adjacent the other end thereof, a horizontally disposed fan and motor assembly within and spaced laterally from the outer housing and having an axially extending flange at one end forming a horizontally directed air inlet passageway, and a flange on said duct element surrounding said horizontally directed aperture and extending coaxially of and connected to said axially extending flange to support said one end of the fan and motor assembly on the duct element and form an enclosed air passageway between said horizontally directed aperture and said one end of the fan and motor assembly.

4. In a vacuum cleaner of the tank type, an outer housing, a vertically arranged compartment within the outer housing, a dust separating bag vertically positioned in the compartment with the bottom of the bag being vertically spaced from the bottom of the compartment, means forming an aperture in the side of the compartment intermediate the bottom of the dust bag and the bottom of the compartment, a vertically dis-

posed air duct externally of the compartment and spaced from the outer housing, said air duct communicating at one end with said aperture in the side of the compartment and being provided with a horizontally directed aperture adjacent the other end thereof, a horizontally extending flange surrounding said horizontally directed aperture, a horizontally disposed fan and motor assembly within and spaced from the outer housing, and having means on one end thereof forming an inlet air passageway to the fan, a flange on said one end of the fan and motor assembly disposed coaxially of said horizontally extending flange in registry with said inlet air passageway, one of said flanges being of a lesser diameter than and extending within the other, and a resilient collar disposed intermediate said flanges to form a resilient connection therebetween whereby said one end of the fan and motor assembly is supported by said air duct.

5. In a vacuum cleaner of the tank type, the combination comprising an outer housing, a vertically arranged compartment within the outer housing and having its upper end open, a dust separating bag vertically positioned in the compartment with the bottom of the bag being vertically spaced from the bottom of the compartment, means providing an aperture in the side of the compartment intermediate the bottom of the dust bag and the bottom of the compartment, a fan and driving motor assembly disposed horizontally within and spaced laterally from the outer housing externally of the compartment and having air inlet means on one end, a flange on said one end of the fan and motor assembly forming an enclosed horizontally directed air passageway communicating at one end of said air inlet means, a vertically disposed duct element mounted on the outer periphery of the compartment to form in cooperation with a portion of the outer periphery of the compartment and an enclosed air passageway within and spaced laterally of the outer housing and communicating at one end with said aperture in the compartment, the duct element being provided with a horizontally directed aperture adjacent its other end in sealed communication with the other end of said horizontally directed passageway, the fan and motor assembly being provided with an air outlet passageway exhausting into the interior of the outer housing, and means forming an aperture in the outer housing through which exhaust air from the fan and motor assembly may flow outwardly of the outer housing.

6. In a vacuum cleaner of the tank type, an outer housing, a fan and motor assembly disposed within the outer housing and having an axial extension at one end, mounting means supporting the fan and motor assembly relative to the outer housing, a plate member mounted on said axial extension intermediate the mounting means and said one end of the fan and motor assembly, the plate member being connected to the fan and motor assembly to substantially prevent relative rotation of the plate member about the rotational axis of the fan and motor assembly, the mounting means and the plate member each being provided with a projection spaced radially outwardly of the axial extension, the projections being oppositely directed axially of the fan and motor assembly, and a resilient member disposed intermediate the mounting means and the plate member and having means to respectively receive and engage said projections whereby relative rotation of the plate member and mounting means will be resiliently restricted.

7. In a vacuum cleaner of the tank type, an outer housing, a fan and motor assembly disposed within the outer housing and having an axial extension at one end, a mounting bracket having means receiving a portion of and supporting said axial extension relative to the outer housing, a plate member mounted on said axial extension and having a finger portion extending axially of the fan and motor assembly, means on said one end of the fan and motor assembly engaging said finger portion to

substantially prevent relative rotation of the plate member and fan and motor assembly, a projection on the plate member spaced radially outwardly of the axial extension and extending axially away from said one end of the fan and motor assembly, a projection on the mounting bracket spaced radially outwardly of the axial extension and extending axially toward the fan and motor assembly, and a resilient member mounted on the axial extension intermediate the plate member and the mounting bracket and provided with a pair of apertures respectively receiving the projections on the plate member and mounting bracket.

8. In a vacuum cleaner of the tank type, an outer housing, a fan and motor assembly disposed within the outer housing and having an axial extension and in a radially disposed rib at one end, a mounting bracket on the outer housing, means on the mounting bracket receiving a portion and supporting said axial extension, a plate member mounted on the axial extension and provided with a bifurcated finger portion directed axially of the fan and motor assembly for engagement with either side of said radially disposed rib, the plate member being provided with a struck out tab disposed radially thereof and extending toward said mounting bracket, a struck out tab on the mounting bracket disposed radially thereof and extending toward the plate member, the tabs on the plate member and mounting bracket being diametrically disposed relative to the longitudinal axis of the axial extension, and a resilient member disposed intermediate the plate member and the mounting bracket and being provided with a pair of slots extending radially thereof and respectively receiving the struck out tabs on the plate member and mounting bracket.

9. In a vacuum cleaner of the tank type, an outer housing, a fan and motor assembly disposed horizontally within the outer housing and provided with an axial extension at one end thereof, a motor mounting bracket mounted on the outer housing having a cup-like portion provided with a centrally located aperture coaxially receiving said axial extension, the edge portion of said aperture being spaced radially outwardly from the outer diameter of said axial extension, a resilient member disposed within said cup-like portion and surrounding a por-

tion of and supporting said axial extension relative to the mounting bracket, a projection on said cup-like portion extending axially toward the fan and motor assembly, a plate member mounted on the axial extension intermediate said one end of the fan and motor assembly and the mounting bracket and provided with a projection extending axially of the fan and motor assembly toward the cup-like portion, said plate member being connected to the fan and motor assembly to substantially prevent relative rotation of the plate member and fan and motor assembly, and a second resilient member mounted on the axial extension intermediate the cup-like portion and the plate member and provided with a pair of apertures respectively receiving the projections on the cup-like portion and plate member to restrict relative rotation therebetween.

10. In a vacuum cleaner of the tank type, an outer housing, a fan and motor assembly horizontally disposed within the outer housing, mounting means on the outer housing for the support of one end of the fan and motor assembly, a resilient member disposed between the mounting means and said one end of the fan and motor assembly, and oppositely directed means supported on the mounting means and said end of the fan and motor assembly engaging said resilient member to impede and limit rotation of said fan and motor assembly about the rotational axis thereof and relative to said mounting means.

11. In a vacuum cleaner of the tank type as set forth in claim 1, wherein said horizontally disposed fan and motor assembly have air discharge means communicating with the interior of said outer housing, and with said outer housing having independent air outlet means.
